ATTORNEY.

UNITED STATES PATENT OFFICE

ERNEST J. NOEL, OF WAUREGAN, CONNECTICUT

BUNCH BUILDER

Application filed January 10, 1928. Serial No. 245,765.

My invention relates to a bunch builder device, for use in connection with spinning and twisting machines.

In the embodiment of the invention, the bunch builder device is preferably in the nature of an attachment, and may be readily applied to different types of spinning and twisting machines, without materially altering the construction of the same.

10 The device embodies a traverse or builder cam, which moves the builder arm up and down, during the normal operation of the spinning or twisting machine, and this builder arm is connected with the usual rocker 15 shaft which operates the ring rail. Operating in connection with the main traverse or builder cam is an auxiliary traverse or builder cam, having a greater number of short cam faces, to engage with the roller of the builder arm. This auxiliary traverse or 20 builder cam is normally idle during the normal operation of the main traverse cam. When the ring rail is lowered to doff the frame, the builder arm descends below its 25 lowermost stroke, during the normal operation of the builder arm, and this causes the forward end of the auxiliary cam to engage over the builder arm roller. When the spinning frame is again started, the builder arm 30 is raised, and the builder arm roller raises the auxiliary cam. Upon this operation, the auxiliary cam is automatically locked for rotation with the main cam or its shaft. The auxiliary cam now passes over in engagement 35 with the builder arm roller, and hence the builder arm roller is given an increased number of up and down movements, with the result that the yarn is wound in a bunch, when the spinning frame is first started after doffing. 40 When the auxiliary cam is passed from engagement with the builder arm roller, it turns with the main cam, until it assumes an inverted position, at which time it is automatically unlocked from the main cam or 45 main cam shaft, and hence remains idle during the usual spinning or twisting operation, prior to doffing.

In the accompanying drawings, forming a 50 part of this specification, and in which like

numerals are employed to designate like parts throughout the same,

Figure 1 is a side elevation of a bunch builder device embodying my invention, showing the builder arm in the raised position, upon starting up the machine, 55

Figure 2 is a transverse section, taken on line 2-2 of Figure 1,

Figure 3 is a view similar to Figure 1, with the auxiliary cam inverted, and released from its locking connection with the main cam shaft, 60

Figure 4 is a similar view, showing the auxiliary cam unlocked, and in the lowered position, and the builder arm raised, and, 65

Figure 5 is a similar view with the builder arm lowered, after doffing.

In the drawings, wherein for the purpose of illustration, is shown a preferred embodiment of my invention, the numeral 5 designates a builder arm pivoted at 5', to swing in a vertical plane, and which is suitably connected by means of a chain 6 or the like, with the usual rocker shaft, not shown, which is employed to operate the ring rail. The 70 numeral 7 designates a main traverse or builder cam, having cam faces 8, to engage with a roller 9, carried by the builder arm 5. When the spinning machine is operating, the builder arm 5 is in the elevated position, and the roller 9 is positioned in the path of travel of the cam faces 8 and the builder arm 5 is given an up and down swinging movement, which causes the ring rail to move up and down, as is well known in spinning or twisting machines. The elements above described are thus well known in the ordinary spinning or twisting machine, and it is, therefore, thought to be unnecessary to give any further disclosure of the spinning or twisting machine. The builder device or attachment includes an arm 10, arranged upon one side of the main cam 7. This arm has a longitudinal slot 11, which slidably receives the drive shaft 12 of the main cam 7. The arm 10 is provided at its outer end with an auxiliary cam 13, preferably formed integral therewith, and this auxiliary cam is preferably provided 80 with a relatively large number of short cam faces 14. The roller 9 is positioned to extend 85

90

95

100

across the main cam 7 and auxiliary cam 13, for engagement therewith.

Means are provided to lock the arm 10 for rotation with the main cam 7, such means including a lateral projection or bracket 15, provided upon its inner end with teeth 16, to engage and interlock with teeth of a gear 17, which is rigidly mounted upon the shaft 12, upon the outer side of the arm 10. The arm 10 extends upon the opposite side of the shaft 12, from the auxiliary cam 13, and a latch 18 is pivoted to the arm 10, at 19. This latch has a locking shoulder 20 and a stop 21. The main cam 7 may rotate in the direction of its arrow, but may be rotated in the opposite direction, in which event the latch 18 is reversed and its pivot 19 inserted in an opening 21, formed upon the arm 10.

In operation, the main cam 7 may be turned in the direction of its arrow, and the builder arm 5 will be in the raised operative position, as indicated in Figures 1 to 4, inclusive. The forward end 13' of the auxiliary cam engages behind the roller 9 at about the point 9^a, Figure 4, and does not ride over the roller 9. The arm 10 is now unlocked from the shaft 12, as the teeth 16 are out of engagement with the teeth of the gear 17. Hence the main cam 7 may continue to rotate while the auxiliary cam 13 remains idle. When the ring rail is lowered to doff the frame, the builder arm 5 moves downwardly below any elevation which it assumes during the normal operation of the spinning or twisting machine, as shown in Figure 5. The auxiliary cam 13 will now gravitate toward the roller 9, and the forward end 13' of the auxiliary cam 13 will now engage over the roller 9. When the spinning frame is again started, the builder arm 5 rises to its normal elevation, and the roller 9 will not engage beneath the auxiliary cam. When the builder arm 5 rises, as stated, it elevates the arm 10, and the teeth 16 engage with the teeth of the gear 17, and about this time, latch 18 gravitates to the lowered position, and shoulder 20 engages over the shaft 12. The arm 10 is now locked for rotation with the shaft 12. With the builder arm 5 thus raised, the auxiliary cam 13 passes over the roller 9 and the cam faces 14 impart to the builder arm 5 a greater number of up and down movements. When the auxiliary cam 13 clears the roller 9, the cam faces 8 of the main cam again co-act with the roller 9. When the auxiliary cam 13 has assumed the inverted position, Figure 3, the latch 18 gravitates to the open position, disengaging the shaft 12, and hence teeth 16 disengage the teeth of the gear 17, when the auxiliary cam 13 again assumes the lowered position. When the auxiliary cam 13 again reaches the roller 9, its forward end 13' engages behind the same, at about the point 9^a, and hence the auxiliary

cam remains inactive until the frame is doffed.

It is to be understood that the form of my invention, herewith shown and described, is to be taken as a preferred example of the same, and that various changes in the shape, size and arrangement of parts may be resorted to without departing from the spirit of my invention, or the scope of the subjoined claims.

Having thus described my invention, I claim:

1. In a spinning or twisting machine, a main cam, a pivoted builder arm having a part to engage with the main cam, a reciprocatory auxiliary cam arranged near the main cam to engage with the part and movable generally radially of the main cam, said auxiliary cam being free from connection with the builder arm, and means to lock the auxiliary cam against such radial movement in one direction and to cause the same to rotate with the main cam.

2. In a spinning or twisting machine, a main cam, a movable builder arm, a reciprocatory auxiliary cam arranged near the main cam to operate the builder arm and movable bodily radially of the main cam, and means to lock the auxiliary cam against such radial movement and to cause the same to rotate with the main cam.

3. In a spinning or twisting machine, a main cam, a movable builder arm arranged to be operated by the main cam, a one-piece reciprocatory auxiliary cam arranged near the main cam and adapted to move bodily radially with relation thereto and to operate the builder arm, and means to lock the auxiliary cam against radial movement and to cause the same to rotate with the main cam.

4. In a spinning or twisting machine, a movable builder arm having an actuating element, a main cam arranged to engage the actuating element, reciprocatory auxiliary cam arranged near the main cam and movable radially outwardly beyond the diameter of the main cam to assume a position behind the actuating element, the auxiliary cam passing upon the top of the actuating element when the builder arm is depressed when the machine is doffed, and means to lock the auxiliary cam against radial movement and to cause the same to rotate with the main cam.

5. In a spinning or twisting machine, a main cam, a shaft carrying the main cam, a generally radial arm having an elongated slot to receive the shaft, a latch carried by the arm and adapted to engage the shaft to hold the arm against longitudinal movement, an auxiliary cam carried by the arm and arranged near the main cam, and a movable builder arm having a part to be engaged by the main cam and the auxiliary cam.

6. In a spinning or twisting machine, a

main cam, a shaft carrying the main cam, a generally radial arm having an elongated slot receiving the shaft, a movable latch carried by the arm and engaging the shaft to lock the arm against radial movement, an auxiliary cam carried by the arm and arranged near the main cam, said main cam and auxiliary cam having means associated therewith to cause the auxiliary cam to rotate with the main cam when the arm is locked against outward movement, and a movable builder arm having a part to be engaged by the main cam and the auxiliary cam.

7. In a spinning or twisting machine, a main cam, a shaft carrying the main cam, a toothed member mounted upon the shaft, an arm having a longitudinal slot receiving the shaft and provided with a toothed member to engage with the first named toothed member, a gravity operated latch pivoted upon the arm and adapted to engage with the shaft to hold the arm against radial movement in one direction, an auxiliary cam carried by the arm, and a builder arm having an upstanding part arranged in the path of travel of the main cam and the auxiliary cam.

8. In a spinning or twisting machine, a main cam, a movable builder arm having a part to be actuated by the main cam, a reciprocating auxiliary cam arranged near one side of the main cam and adapted to move generally radially with relation thereto, means actuated upon the inward movement of the reciprocating auxiliary cam to lock the same with the main cam so that they rotate together, and a gravity operated latch to lock the auxiliary cam in the inner position when shifted thereto, said latch automatically releasing the auxiliary cam, when said latch becomes inverted.

9. In a spinning or twisting machine, a main cam, a movable builder arm having a part actuated by the main cam, a reciprocating auxiliary cam arranged near and upon one side of the main cam and movable generally radially with relation thereto, an auxiliary cam being arranged to engage said part, means to lock the auxiliary cam and the main cam together so that they rotate together when the auxiliary cam is shifted inwardly, and separate means to lock the auxiliary cam against outward radial movement during a part of its rotation after it has been shifted to the inner position.

55 10. In a spinning or twisting machine, a main cam, having cam faces, a movable builder arm having a part to be engaged by said cam faces, a reciprocating auxiliary cam arranged near and upon one side of the main cam and movable radially with relation thereto, said auxiliary cam having a plurality of relatively short cam faces which are adapted to actuate said part, means to lock the reciprocating auxiliary cam with the main cam so that they turn together when the auxiliary

cam is shifted inwardly, and means to lock the auxiliary cam against outward radial movement after it has been shifted to the inner position.

In testimony whereof I affix my signature. 70
